ATTORNEY.S

UNITED STATES PATENT OFFICE.

CARMEL C. BLANCO, OF HOUSTON, TEXAS.

CHOKE CONTROL.

Application filed December 10, 1923, Serial No. 679,636. Renewed June 19, 1925.

To all whom it may concern:

Be it known that I, CARMEL C. BLANCO, subject to the King of Italy, residing at Houston, in the county of Harris and State 5 of Texas, have invented certain new and useful Improvements in Choke Controls, of which the following is a specification.

This invention relates to new and useful improvements in choke control.

10 One object of this invention is to provide a means for "choking" or rendering the mixture going from the carburetter to the cylinders of the engine richer, and to maintain this rich mixture until the engine is warmed 15 up or so long as it may be necessary.

With the above and other objections in view this invention has particular relation to certain novel features of construction, 20 operation and arrangement of parts, an example of which is given in this specification and illustrated in the accompanying drawings, wherein:—

25 Figure 1 is a side elevation of a Ford engine with my device attached to the dash of the body of the car, and with suitable rods running therefrom to the carburetter and instrument board of the car.

30 Figure 2 is a side elevation of the device and,

35 Figure 3 is an edge view thereof.

Referring now more particularly to the drawings wherein like numerals of reference refer to similar features of the device in each figure, the numeral 4 refers to the 40 outwardly turned end lug of the bracket 5. The lug 4 has radiating corrugations as 6 preferably arranged in a circular row. This bracket 5 is provided with holes 7, 7. Bolts 6 pass through these holes and 45 through the dash 9 of the car and are held in fixed position by means of the nuts 10. A fluted disc 11 having the arms 12 and 13 is adapted to lie against and cooperate with the fluted side of the lug 4, and the bolt 14 passes through these central bearings in 50 these two elements, and also passes through the spider 15, and the lock washer 16, all of which are held operatively together by

means of the nut 17. The spider 15 has radiating flexible fingers which rest against 50 the lug 4, causing the central part of the spider to bear yieldingly against the washer 16 to lock the nut 17 against detachment.

To the shorter arm 12 a rod 18 is attached and passes through both the dash 9 55 and the instrument board 19, while the rod 20 is attached at one end to the arm 13, and at the other end to the arm 21 of the butterfly valve in the carburetter 22.

When the engine is cold a pull upon the 60 rod 18 will raise arms 12 and 13 and through them rod 20 and arm 21 thus causing the butterfly valve to cut off a portion of the cold air passing through the carburetter and thus give a richer mixture to the engine. 65

A device of this character is cheaply made, very effective in actual operation and is easily installed on the present type of Ford cars.

What I claim is:—

A device of the character described including a bracket having one end upturned forming a lug, said lug being provided with radiating corrugations, means for securing said bracket to the dash of an automobile, a 70 bell crank formed of a fluted disc and two radiating arms, said disc fitting against the corrugated side of said lug, a spider having flexible fingers fitted against the other side of said lug, a bolt passing through said disc, 75 lug and spider, a securing nut threaded onto said bolt and resting against said spider, a rod extending through the instrument board, and dash of the vehicle and attached to the free end of one of said arms, and 80 another rod connected at one end to the free end of the other arm, and at its other end connected with the air inlet valve of the vehicle carburetter. 85

In testimony whereof I have signed my 90 name to this specification in the presence of two subscribing witnesses.

CARMEL C. BLANCO.
